(57) **CLAIM**

The ornamental design for a programmable controller with safety controller, as shown and described.

DESCRIPTION

FIG. 1 is a top, front, and right side perspective view of a programmable controller with safety controller showing our new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a top, front, and right side perspective view in an opened condition.

The dashed broken lines in the figures show portions of the programmable controller with safety controller that form no part of the claimed design. The dot-dashed broken lines in FIGS. 1 and 7 show boundary that forms no part of the claimed design. The boundary extends from a bottom surface to an inside corner at the intersection between the right side of main body of programmable controller and the circular terminals.

1 Claim, 5 Drawing Sheets
